UNITED STATES PATENT OFFICE.

HOWARD M. SANKEY, OF ALLIANCE, OHIO.

COAL POCKET.

1,411,190.

Specification of Letters Patent. Patented Mar. 28, 1922.

Application filed January 9, 1920. Serial No. 350,329.

To all whom it may concern:

Be it known that I, HOWARD M. SANKEY, a citizen of the United States, and a resident of Alliance, in the county of Stark and State 5 of Ohio, have invented a new and Improved Coal Pocket, of which the following is a full, clear, and exact description.

This invention relates to improvements in coal pockets, an object of the invention being to provide a coal pocket having an improved arrangement of pivoted chute, the latter when in operative position, spaced at its upper end from the wall of the hopper, whereby an entrance is provided for a suitable tool to loosen or break up an arch of coal which might form therein to interfere with the free flow from the pocket.

A further object is to provide a coal pocket which is especially designed for use 20 in connection with lump coal and so construct the pocket as to control the flow of coal and permit the loosening of accumulating lumps which would interfere with the proper operation of the pocket.

25 A further object is to provide a coal pocket which can be conveniently utilized for loading so as to direct the coal wherever desired into the vehicle being loaded, and which is of extremely simple construction, 30 strong and durable in use.

With these and other objects in view the invention consists in certain novel features of construction, and combinations and arrangements of parts as will be more fully 35 hereinafter described and pointed out in the claims.

In the accompanying drawings—

Figure 1 is a sectional plan view on the line 1—1 of Figure 2;

40 Figure 2 is a view in vertical longitudinal section on the line 2—2 of Figure 1; and

Figure 3 is a view in front elevation of Figure 2.

45 1 represents the bottom of an ordinary coal bin which directs coal into a hopper 2, the latter having at its lower rear portion an outlet opening 3 for the discharge of the coal onto a chute 4. The chute 4 is pivotally mounted on a transverse shaft 5 supported in hangers 6 and is composed preferably of sheet metal having channel bars 7 at its sides extending rearwardly and upwardly beyond the end of the chute and provided with 50 counter-balanced weights 8.

If desired, I may also provide cables 9

connected to the forward or free end of the chute, passed over pulleys 10 and secured to a fixed part of the coal pocket. Counterbalanced weights 11 with their pulleys 12 60 are supported on the cables 9 to give the necessary counterbalance to the chute.

It is, of course, to be understood that I may use either the extended channels 7 with their weights 8 or the cables 9 and their 65 counterweights 11 as desired, but in most cases will use but one of these counterbalancing means.

The opening 3 in the bottom of the hopper 2 is extended partially around the lower 70 front portion as indicated at 13, and a sliding gate 14 mounted in angle iron guide rails 15 is adapted to control the outlet of coal from the hopper. It will be noted that by moving the gate 14 longitudinally not 75 only the quantity of coal discharged can be controlled, but also the direction of such discharge of coal.

The gate 14 is connected by a link 16 with a crank arm 17, the latter fixed to a shaft 18 80 supported in suitable brackets 19. The shaft 18 is extended to one side of the coal pocket and is provided with a lever 20 which can be manipulated at one side of the vehicle being loaded without interfering with 85 the loading operation.

The chute 4 is provided between its ends with a grate or screen 21 and below this grate or screen a slack pocket 22 is provided having a hinged outlet gate 23 at its lower 90 end controlled by a locking arm 24 which is pivotally connected to the gate and engages a keeper 25 to normally hold the gate in closed position.

I would call particular attention to Fig. 95 2 wherein it will be noted that the upper end of the chute is spaced from the lower end of the hopper and an angle iron bar 26 is secured to this end of the chute. This space between the bar 26 and the end of the 100 hopper affords an entrance for a poker or other tool to dislodge lumps of coal which have clogged the outlet of the hopper, and the bar 26 acts as a supporting bridge or guide for the tool so that the operator on the 105 ground can easily manipulate the same to clear the passage and cause a free flow of coal from the pocket.

In handling bituminous coal having large lumps, it is necessary from time to time to 110 dislodge accumulating arches of these lumps which clog the outlet and by providing a

chute having its end adjacent the hopper spaced from the hopper and providing a free opening or entrance for a tool to dislodge accumulating piles of lumps, a free flow can be maintained or at least restored from time to time. Also this operation can be accomplished with a minimum of breakage of the lumps as it is desirable to maintain the lumps as large as possible and the use of the poker is not to break up lumps but merely to break an arch or dislodge an accumulation which stops the flow. In order to provide this passage or free space between the chute and the end of the hopper it is obvious that the chute is open ended and the space will be ample for the manipulation of the tool without allowing any coal to escape through said opening or space.

It will be noted that the slide 14 is projected across the hopper cutting off the flow of coal but leaving a clear opening at the top. In other words by positioning the slide as indicated a lump can not block the closing movement of the slide as the flow is effectually cut off without the slide reaching entirely to the rear wall of the hopper.

Various slight changes may be made in the general form and arrangement of parts described without departing from the invention, and hence I do not limit myself to the precise details set forth but consider myself at liberty to make such changes and alterations as fairly fall within the spirit and scope of the appended claims.

35 I claim:

1. The combination with a hopper having a bottom inclining downwardly from its forward to its rear end and terminating short of the extreme lower end of the hopper, of inclined guides secured to the inner faces of the sides of the hopper above the lower end of the hopper and projecting forwardly just below the lower end of the bottom, and a gate valve movable in said guides and adapted to control the outlet from the hopper.

45 2. The combination with a hopper having

a bottom inclining downwardly from its forward to its rear end and terminating short of the extreme lower end of the hopper, of inclined guides secured to the inner faces of the sides of the hopper above the lower end of the hopper and projecting forwardly just below the lower end of the bottom, a gate valve movable in said guides and adapted to control the outlet from the hopper, hangers depending from the sides of the hopper, and a chute pivotally supported near its rear end by said hangers and extending across and spaced from the open bottom of the hopper.

3. The combination with a hopper having a bottom inclining downwardly from its forward to its rear end and terminating short of the extreme lower end of the hopper, of inclined guides secured to the inner faces of the sides of the hopper above the lower end of the hopper and projecting forwardly just below the lower end of the bottom, a gate valve movable in said guides and adapted to control the outlet from the hopper, hangers depending from the sides of the hopper, a chute pivotally supported near its rear end by said hangers and extending across and spaced from the open bottom of the hopper, and a tool guiding bar secured to the rear end of the chute.

4. The combination with a hopper having a bottom inclining downwardly from its forward to its rear end and terminating short of the extreme lower end of the hopper, of inclined guides secured to the inner faces of the sides of the hopper above the lower end of the hopper and projecting forwardly just below the lower end of the bottom, a gate valve movable in said guides and adapted to control the outlet from the hopper, hangers depending from the sides of the hopper, a chute pivotally supported near its rear end by said hangers and extending across and spaced from the open bottom of the hopper, counterbalanced means moving the chute, and manually operated means for moving the gate valve.

HOWARD M. SANKEY.
